[57] CLAIM

The ornamental design for a measuring receptacle with cup wall removable from handle attached bottom, substantially as shown and described.

DESCRIPTION

FIG. 1 is a perspective view of a measuring receptacle with cup wall removable from handle attached bottom showing my new design;

FIG. 2 is a top plan view thereof;

FIG. 3 is a bottom view thereof;

FIG. 4 is a side elevational view thereof; and

FIG. 5 is an end view thereof.

The side view not shown is the mirror image of the side view shown in FIG. 4.
